UNITED STATES PATENT OFFICE

ISADORE M. JACOBSON, OF CHICAGO, ILLINOIS, AND STARR TRUSCOTT, OF
BIRMINGHAM, OHIO

AIRCRAFT COVERING

Application filed March 6, 1925. Serial No. 13,617.

(GRANTED UNDER THE ACT OF MARCH 3, 1883, AS AMENDED APRIL 30, 1928; 370 O. G. 757)

This invention relates to improvements in fabrics for aircraft and more particularly to the construction of gas cells for the rigid types of balloons although it is, of course, to be understood that it is applicable to the non-rigid type as well.

In our co-pending applications filed Apr. 11, 1925, and bearing Serial Nos. 22,346, 22,347, and 22,348, were given descriptions of various fabrics for the gas cells of rigid airships using cellulose and other films as a substitute for goldbeater's skins. In these fabrics the general practice was to form a film of cellulose, or other impermeable membrane, and apply it by means of an adhesive to the foundation cloth. In the fabrics which are now described the process is to form the impermeable film directly upon the cloth or upon a film already prepared upon the cloth and thus avoid the necessity of handling the impermeable film separately from the cloth or foundation.

By this method it is possible to construct not merely fabrics containing one layer of cloth on which the film is built up, but also to produce fabrics containing several layers of cloth with an impermeable film, or several impermeable films incorporated in the layers between the cloth.

When intended for use as a substitute for goldbeater's skin fabric the fabric in question may be produced by coating a rubberized or other proofed fabric with viscose or other water-soluble derivative of cellulose that is subsequently reverted to cellulose itself. The product thus obtained is a smooth, flexible fabric resembling greatly in appearance goldbeater's skin fabric. The film of cellulose formed on the rubber or other proofed surface of the fabric is tough, plastic, and adheres well to the surface. It is superior to goldbeater's skin in that it is more plastic and may be stretched with the fabric without cracking or breaking. It is superior to cellophane in that it forms a firmer bond with the rubber or other proofed surface and eliminates also a number of steps in the manufacture of the gas cell fabric.

It is, therefore, one of the objects of the present invention to provide a more reliable

and efficient fabric of the above general character which may be less expensively manufactured and adapted to overcome various objections heretofore experienced.

Other objects will be in part obvious and in part hereinafter pointed out with the following description of the invention.

A more comprehensive understanding of the invention may be had from the accompanying drawings, wherein

Figure 1 is a conventional cross sectional view of a fabric constructed in accordance with my invention, and

Figure 2 is a modified form thereof wherein is illustrated a multiple-ply fabric.

In carrying out the invention we prefer to start with Pará rubber although other kinds may be used. Combined with a suitable vulcanizing agent, Pará rubber is spread, in the form of a dough, over a light weight balloon cloth and the rubberized cloth thus formed is vulcanized just sufficiently to prevent it from sticking to itself. A coat of gelatin or glue adhesive, containing suitable plasticizing and stabilizing ingredients is applied to the rubber surface and dried. Successive coats of viscose solution are then applied until the viscose film reaches the desired weight. The viscose is then reverted to cellulose by passing through a bath containing an aqueous solution of sodium bisulfite, washed with water and finally immersed in an aqueous solution of glycerine in order to render it plastic. The fabric is then dried and a coat of varnish applied to the cellulose to protect it from moisture.

Instead of using the coating above described the various compounds described in our co-pending applications above referred to may be applied directly to the proofed fabric, if so desired.

In carrying out the manufacture of the fabric, it is preferred to use an apparatus somewhat similar to that described in patent to Brandenberger, No. 991,267, modified as may be necessary so that the viscose upon coming out of the hopper will flow directly upon a rubberized or other proofed fabric and then proceed through various

chemical operations of chemical treatment, washing, etc., outlined therein.

It will, of course, be understood that when the fabric is modified for use on non-rigid balloons substantially the same process is followed with the omission of the protecting coating of varnish. This fabric is cemented together with a rubberized fabric by means of a suitable adhesive. Rubber cement or gelatin adhesives will probably be suitable for this purpose. In this manner, two, three, and four ply fabric may be easily built up, the viscose films acting as the gas impermeable membranes.

In the manufacture of the fabrics outlined above, we do not limit ourselves to the use of rubber. Any type of proofing which has the desired properties may be used. We do not limit ourselves to the use of viscose but may use the aqueous dispersion of any cellulose derivative. The use of a cementing adhesive between the viscose and the proofed fabric may, if desired, be omitted. We do not limit ourselves to the vulcanization of the rubberized fabric prior to the coating with viscose. In some cases, particularly in the case of the multiple-ply fabrics, it will probably be desirable to vulcanize the fabric after it is assembled. We do not limit ourselves to the use of the agents above mentioned for reverting viscose to hydro-cellulose.

It will thus be seen that the present invention contemplates the manufacture of fabrics particularly adapted for the purpose above set forth among others which may be inexpensively performed and the resulting material will be highly reliable, suitable and efficient in use and operation.

The invention herein described may be manufactured and used by or for the Government of the United States for governmental purposes without the payment to us of any royalty thereon or therefor.

What we claim is:—

1. A flexible fabric impermeable to gases for the construction of gas cells consisting of a rubberized base fabric and a layer of reverted plasticized cellulose.
2. A flexible fabric impermeable to gases for gas cell construction consisting of a rubberized base fabric, a layer of reverted plasticized cellulose and a moisture proofing film.
3. A flexible fabric impermeable to gases for gas cell construction consisting of a rubberized base fabric, an adhesive thereon, a layer of reverted cellulose impregnated with a plasticizing agent.
4. A flexible fabric impermeable to gases for gas cell construction consisting of a rubberized base fabric, an adhesive thereon, a layer of reverted cellulose, a plasticizing agent applied thereto, and a moisture proofing film exterior thereof.
5. A flexible fabric impermeable to gases

for gas cell construction consisting of a rubberized base fabric, an adhesive thereon, a layer consisting of reverted cellulose, a second layer of rubberized fabric, a second layer of reverted cellulose, and a water proofing film applied to the outside thereof.

6. A method of rendering a fabric flexible and impermeable to gases consisting in rubberizing a fabric, applying an adhesive thereto, spreading a cellulose derivative thereover, regenerating cellulose by the subjection of the thus prepared fabric to baths, plasticizing the regenerated cellulose, and waterproofing the built up fabric.

7. A method of rendering a fabric flexible and impermeable to gases consisting in rubberizing a fabric, applying an adhesive containing plasticizing and stabilizing ingredients, drying said adhesive, applying a coating of viscose solution, reverting said viscose solution to cellulose by subjecting the thus prepared fabric to baths, plasticizing the regenerated cellulose, and waterproofing the built up fabric.

8. A flexible fabric impermeable to gases for the construction of gas cells consisting of a rubberized base fabric and a film of plasticized reverted cellulose rubber.

9. A flexible fabric impermeable to gases for gas cell construction consisting of a rubberized base fabric, a film of plasticized reverted cellulose, and a moisture proofing layer thereover.

10. A flexible fabric impermeable to gases for gas cell construction consisting of a rubberized base fabric, an adhesive thereon, and a film of reverted cellulose rubber impregnated with a plasticizing agent.

11. A flexible fabric impermeable to gases for gas cell construction consisting of a rubberized base fabric, an adhesive thereon, a film of reverted cellulose rubber, a plasticizing agent applied thereto, and a moisture proofing film exterior thereof.

12. A flexible fabric impermeable to gases for gas cell construction consisting of a rubberized base fabric, an adhesive thereon, a film of reverted cellulose rubber, a second layer of rubberized fabric, a second film of reverted cellulose rubber, and a water proofing film applied to the outside thereof.

Signed at Washington, District of Columbia, this 31st day of January, 1925.

ISADORE M. JACOBSOHN.
STARR TRUSCOTT.
